Patented Feb. 21, 1922.

Inventor
William Gordon

By his Attorney

Edward Holland

UNITED STATES PATENT OFFICE.

WILLIAM GORDON, OF UNION, NEW JERSEY.

WRENCH.

1,407,528.

Specification of Letters Patent. Patented Feb. 21, 1922.

Application filed August 30, 1919. Serial No. 320,878.

To all whom it may concern:

Be it known that I, WILLIAM GORDON, a citizen of the United States, and a resident of the town of Union, county of Hudson, 5 and State of New Jersey, have invented certain new and useful Improvements in Wrenches, of which the following is a specification.

This invention relates to improvements in 10 wrenches.

One object of this invention is to produce a wrench which is not only capable of quick manipulation but also has means for permitting fine adjustment or tightening up upon 15 a nut or the like to any desired degree.

Another object of my invention is to produce a wrench in which one of the jaws is capable of the fine adjustment procurable by the use of a screw or worm and may also, 20 by the simple manipulation of a trigger-like element be released from operative engagement with the screw or worm so as to permit rapid or quick movement of the jaw to full open position either by gravity when 25 the wrench is held in proper position or by hand in other positions.

Another object of my invention is to provide in a screw-adjusted wrench of the character above described, a spring which is 30 adapted automatically, upon the releasing by said trigger-like element of the screw from operative engagement to instantaneously move the jaw to full open position, thus procuring quick and positive movement to 35 such full-open position while the wrench is held in any plane.

Still another object of my invention is to produce a wrench of the character above specified in which one of the jaws is movable and adjusted by means of a screw having suitably disposed threads yieldingly retained in operative engagement with suitable rack-teeth on said jaw, whereby the jaw may by direct contact be moved from open position to closed position without actuation of the releasing means for the screw, the screw being automatically released during such closing movement to permit the teeth of the rack to click over threads on said screw into 45 an approximate or initial position for gripping a nut, pipe or the like, and may therefore be further adjusted or tightened up on the nut or pipe to any degree necessary or desirable.

50 In the accompanying drawings in which

similar reference characters designate corresponding parts throughout the several views,

Fig. 1 is a side elevation partly in section of a wrench embodying my invention, the section being taken on the line 1—1 of 60 Fig. 2;

Fig. 2 is a section on the line 2—2 of Fig. 1;

Fig. 3 is an end elevation of the device shown in Figs. 1 and 2; and 65

Fig. 4 is a side elevation of a slight modification illustrating the jaws provided with oppositely disposed teeth or serrations and adapted for use on pipes.

Referring now to these drawings, 1 indicates the head of a wrench having, as illustrated, an integral handle 2 and stationary jaw 3 and also provided with a cavity 4, the walls of which are provided with oppositely arranged ways 5 in which a movable jaw 6 70 is adapted to slide toward and away from the stationary jaw 3 so as to permit the gripping of an object between such jaws.

Said jaw 6 is, as illustrated, provided with side grooves 7 cooperating with the ways 80 5 to permit the inward and outward sliding thereof relatively to the stationary jaw 3, and said jaw is furthermore provided at its rear edge with a rack 8 preferably having, as shown, teeth inclined rearwardly, which 85 are normally retained in operative engagement or in mesh with an adjusting or actuating worm or screw 9 having a thread which is inclined in the opposite direction to said rack-teeth. Obviously the rotation of the 90 worm or screw 9 in one direction will cause the movable jaw to approach the stationary jaw or move from open to closed position, while rotation of the said worm or screw in the opposite direction will cause an opposite 95 or opening movement thereof. Any suitable means, such as the slot 10 and pin 11, may be employed to limit the relative degree or extent of movement between the said stationary and movable jaws.

It is a great desideratum to provide a wrench which is capable of a quick initial adjustment of the jaws for the purpose of approximately fitting the objects, such as nuts, pipes and the like, on which it is desired to operate and which is also capable of fine adjustment for the purpose of finally tightening up upon such object. I therefore provide means by which the movable jaw 6 may be readily and quickly released from 110

engagement or operation by the screw or worm 9 so as to permit independent and quicker manipulation thereof than would be possible by means of such screw adjustment, and I furthermore preferably provide means operable upon the release of the jaw 6 from such actuating screw 9 for automatically moving the movable jaw to full open position. I also furthermore preferably provide means whereby the thread on the screw may, during a closing movement of the wrench, be normally retained in yielding contact with a rack on the jaw, so that the movable jaw may be moved from open to closed position by direct contact without operation of the screw-disengaging device, and the teeth of the rack will be caused to click over the screw thread which will act as a retaining pawl therefor and will automatically latch or lock the jaw in an approximate nut engaging position after which the same may be quickly tightened up or finally adjusted by the use of the said screw. With these ends in view, the screw 9 is mounted in an opening 9^a in the head 1 and is arranged to be movable outwardly and out of engagement or contact with the rack 8 so as to release the jaw 6 from the locking engagement of said screw.

In the preferred embodiment of my invention, the screw 9 is rotatably mounted upon a spindle 12 which is pivotally mounted at its upper end upon a pivot pin 13 which extends transversely through the head 1 and the inner end of said spindle. The lower end of the spindle is mounted to move laterally in a longitudinal slot 14 formed in the said head and preferably has an extension end 12^a extending beyond the head and adapted to serve as a trigger or finger-actuated part for moving the screw 9 pivotally upon its pivot 13 and out of engagement with the rack 8 to release the jaw 6. The screw 9 is preferably yieldingly forced into engagement with the rack by means of the flat spring 15 which, as illustrated, is connected at one side to the extension end 12^a of the spindle 12, and also bears at its opposite side against the wall of the slot 14. The screw 9 which, as aforesaid, is rotatably mounted on the spindle 12 is thus yieldingly held in engagement with the rack 8, and it will be obvious that upon applying closing pressure on the jaw 6, the teeth of the rack 8 will automatically force the spring-pressed screw 9 and spindle 12 to swing outwardly in an arc about the pivot 13 and the teeth of such rack will click over the thread of said screw and teeth on the rack will automatically lock the jaw against movement in the opposite direction, and the relative disposition or inclinations of said thread and rack teeth will enable a more ready and more positive automatic release and locking than would otherwise be the case.

When it is desired to procure a quicker opening of a jaw than is required by the rotation of the screw 9, a pressure on the extension 12^a of the spindle against the action of the spring 15 will cause an immediate freeing of the screw from engagement with the rack, and the jaw 6 may then obviously be opened and if the wrench is held in one plane will be automatically moved by gravity into open position. It is desirable, however, in order to secure quick manipulation, to cause the said jaw upon the freeing of the rack as aforesaid to be moved to full open position automatically while the wrench is in any position, and for this purpose I provide a spring 16 which, as illustrated, is seated at one end in a socket 17 in the jaw 6 and has its opposite end bearing against the inner wall 4^a of the cavity 4. This spring 16 not only automatically forces the jaw 6 into full open position when the rack teeth are released from engagement by the screw 9, but will also tend to force the teeth of the rack 8 into engagement with the thread of the screw 9 and thus assist in the retention and automatic locking of the jaw 6 in any desired position to which it is moved as hereinabove described.

In Fig. 4 I have illustrated a slight modification of the device, in which figure the jaws 3 and 6 are provided with serrations 3^a and 6^a respectively so as to adapt the wrench more particularly for use on pipes, rods or other similar round articles. In other respects the wrench is the same as that illustrated in Figs. 1, 2 and 3.

Having described my invention, I claim:

1. In a wrench, a suitable handle, a head, jaws one of which is movable relatively to the other in said head, a rack on said movable jaw, a screw spindle pivoted at one end in said head and extending outwardly beyond said head to form a finger grip, and a screw rotatably mounted on said spindle adjacent to the rack and adapted to engage the same to move the jaw upon rotation and also movable by the spindle outwardly and away from said rack to release the jaw.
2. In a wrench, a suitable handle, a head, jaws, one of which is movable relatively to the other in said head, a rack on said movable jaw, a screw spindle pivoted at one end in said head and extending outwardly beyond said head to form a finger grip, and a screw rotatably mounted on said spindle adjacent to the rack and adapted to engage the same to move the jaw upon rotation and also movable by said spindle outwardly and away from said rack to release the jaw and a spring for automatically moving said jaw to full open position upon a releasing movement of said screw.
3. In a wrench, a suitable handle, a head,

jaws one of which is mounted in said head to move relatively to the other, a rack on said movable jaw, a screw spindle pivotally mounted at one end in said head adjacent to said rack and having a finger-grip extension at its free end extending beyond said head and movable outwardly and away from the rack, a screw rotatably mounted upon said spindle and adapted to engage 5 said rack when its spindle is in one position and to disengage the same when moved to another position and adapted when in engagement with said rack to move the jaw 10

upon rotation, a spring at the opposite end of said screw spindle for forcing the screw 15 yieldingly into engagement with said rack, and a spring for forcing said jaws into full open position upon manipulation of the said finger-grip extension.

In witness whereof, I have signed my 20 name to the foregoing specification in the presence of two subscribing witnesses.

WILLIAM GORDON.
